UNITED STATES PATENT OFFICE.

HAROLD H. SIMMS, OF ROCHESTER, NEW YORK, ASSIGNOR TO AUTO STROP COMPANY, OF NEW YORK, N. Y., A CORPORATION OF NEW YORK.

RAZOR.

1,133,326.

Specification of Letters Patent. Patented Mar. 30, 1915.

Application filed April 17, 1909. Serial No. 490,564.

To all whom it may concern:

Be it known that I, HAROLD H. SIMMS, of Rochester, in the county of Monroe and State of New York, have invented certain new and useful Improvements in Razors; and I do hereby declare the following to be a full, clear, and exact description of the same, reference being had to the accompanying drawings, forming a part of this specification, and 10 to the reference-numerals marked thereon.

The present invention relates to safety razors and it has for an object to make provision whereby the sharpening or stropping of the blade is made easier.

15 To these and other ends the invention consists in certain improvements and combinations of parts all as will be hereinafter more fully described, the novel features being pointed out in the claims at the end of the 20 specification.

In the drawings: Figure 1 is an enlarged transverse section of one embodiment of the invention; Fig. 2 is an enlarged longitudinal section of the same embodiment with the 25 blade moved from coöperative relation with the guard; Fig. 3 is an enlarged side view of the same embodiment showing the guard and the blade separated and the handle shifted for stropping, a strop being shown 30 in transverse section in coöperative relation to the blade; Fig. 4 is a plan view of the guard; Figs. 5 and 6 are respectively an enlarged vertical and an enlarged longitudinal section of another embodiment in which the 35 blade swings away from the guard to a position parallel with the handle; Fig. 7 is an enlarged view of the embodiment illustrated in Figs. 5 and 6 in which the blade is shifted and a strop is shown in transverse section 40 and in coöperative relation to the blade; Figs. 8 and 9 are respectively an enlarged vertical and an enlarged transverse section of still another embodiment in which the guard frame is detachable from the blade 45 holder; Fig. 10 shows this embodiment adjusted for stropping; Fig. 11 is a side view, partially in section, of another embodiment of the invention, and Fig. 12 is a detail view of the guard frame.

50 In the embodiment of the invention shown in Figs. 1 to 4 the blade and blade holder are movable together bodily away from the guard frame so that a space is formed through which a strop or other sharpener 55 may be passed to coöperate with the blade.

The guard frame 1 preferably has at opposite sides two guard portions 2 of any suitable form, while the blade holder is unsupported between its ends and at its ends may carry supports 3 which serve as guides and 60 coöperate with guide portions formed by the walls of slots 4 in the guard frame 1. The blade may be maintained in coöperative or shaving relation with the guard and also in stropping position by any suitable means. 65 In the present instance, spring tongues 5 and 6 are struck up from the metal supports 3, the tongues 5 coöperating with the under surface of the guard frame to secure the holder in its lowered or shaving position, 70 and the tongues 6 coöperating with the upper surface of the guard frame to secure the blade holder in elevated or stropping position. Laterally turned lugs 7 at the lower ends of the supports 3, or other stops, may 75 limit the upward movement of the support.

The blade holder herein illustrated embodies two plates 8 and 9 held together by a thumb screw 10 or other suitable means to retain between them a blade 11 which, in 80 this instance, has cutting edges on opposite sides to coöperated with the two guard portions 2, the blade being, if desired, held against movement by pins or studs 12. The plate 8 has the supports 3 rigidly secured to 85 the ends thereof and in shaving position it may lie within a depression formed in the top of the guard frame 1 between the guard portions 2, relieving the tongues 5 of any strain during shaving owing to the engagement of 90 the side edges of the plate 8 with the sides of the depression. The under surface of the plate 8 should of course be smooth and its edges may be curved in order to permit the holder to travel freely over a strop or other 95 sharpener.

The handle preferably lies perpendicular to the longitudinal axis of the blade for shaving as this arrangement permits a better shaving action. The guard frame is provided with a suitable means for obtaining this end, said means in this instance embodying a perforated boss 13 which may be internally threaded to receive the end of a handle bolt 14 that is surrounded by a sleeve 105 15 forming the grip of the handle. In this position of the handle, the sleeve or grip thereof is held against rotation preferably by a projection 16 on the boss entering a notch 17 in the end of the sleeve. 110

To the end that the handle and the blade may lie parallel to each other so that the handle will be to one side of the longitudinal axis of the blade for stropping, means is provided for permitting the handle to be shifted to another position on the guard frame. This means may be in the form of a depending member or flange 18 at one end of the guard frame, provided 10 with an internally threaded perforation 19 with the walls of which the end of the bolt 14 is adapted to be engaged in the manner shown in Fig. 3. The grip portion 15 of the handle is now free to rotate so that on each 15 shifting of the direction of movement of the razor over a strop or other sharpener, the blade edges will be shifted into or out of engagement with the sharpener. This is due to the fact that the handle lies on one side 20 of the plane of the blade and turns the blade holder about the longitudinal axis of the blade.

When the parts are in the positions shown in Fig. 3 a strop 20 is passed between the 25 guard and the blade holder and the handle is grasped to move the razor back and forth over the sharpener to sharpen one side of each edge. If it is desired to sharpen the other side the position of the blade in the 30 holder is reversed. After the sharpening has been completed the handle is attached, as shown in Figs. 1 and 2 and the blade holder pressed toward the guard frame. The razor is now ready for use, the handle 35 being held against rotation by the projection 16.

In the embodiment shown in Figs. 5 to 7 one movement of the blade holder is sufficient to separate the guards and the blade 40 and to cause the latter and the handle to lie parallel for stropping. The guard frame 1^a may be substantially the same as that shown in Figs. 1 to 4 with two guard portions 2, but the blade holder, instead of moving 45 bodily away from the guard frame, swings about an axis 21 transverse to the longitudinal axis of the blade 11, the lower plate 8^a being hinged to the guard at one end.

To secure the blade in coöperative or shaving relation to the guards, as shown in Figs. 5 and 6, the guard frame 1^a may carry a 50 spring latch 22 at the end opposite the hinge to coöperate with the free end of the blade holder as shown in Fig. 6, while the position of the blade away from the guards, as shown in Fig. 7, may be maintained by providing a depending arm 23 on the blade holder in 55 proximity to the hinge. This arm coöperates with the under surface of the guard frame, as shown in Fig. 7, to limit the outward movement of the blade holder and a spring latch 24 struck up from the metal 60 of the guard frame coöperates with the arm to secure the blade holder in stropping posi-

tion. The blade 11 has also a double edge and is engaged between its edges by plates 8^a and 9^a forming the holder, the lower plate being smooth on its under surface and lying, when in shaving position, within a depression in the guard frame between the guards 70 2. The plates are held together in any suitable manner. In the present instance, the plate 8^a has a screw 25 journaled therein with its head 26 on the under side of said plate. 75 This arrangement of the screw permits it to be controlled from the handle. The latter comprises preferably a rotatable grip or sleeve 27 surrounding an inner sleeve 28 that has screw threaded connection at one 80 end with a boss 29 on the under surface of the guard frame. Also having screw threaded connection with the inner sleeve 28 at the lower or opposite end of the latter is a nut 30 which by engagement with the lower end 85 of the sleeve 27 is adapted to move the latter axially so that its other or upper end, which is roughened at 31 or is otherwise formed with a clutch face, will be moved into engagement with a roughened or clutch 90 face 32 on the boss 29, thus holding the grip against rotation. Within the inner tube or sleeve 28 is arranged a spindle or rod 33 which at its lower end is provided with a thumb piece 34 and at its upper end has a 95 washer 35 secured thereto to prevent its withdrawal from the inner sleeve 28. This rod or spindle 33 serves as an operating member by which the screw 25 is controlled and to this end it is provided with a projecting portion 36 of non-circular cross section 100 entering into a similarly formed opening 37 in the screw head 26 so that when the rod is rotated the screw will be rotated to tighten or loosen the plate 9^a, respectively, to clamp 105 or to release the blade.

In the embodiment shown in Figs. 8, 9 and 10, the guard frame is adapted to be removed entirely from the blade holder for the purpose of separating the blade and the 110 guard or guards. The blade holder is preferably formed by two plates 8^b and 9^b between which the double edged blade 11 is held, pins 12^b on plate 8^b passing through the blade and the plate 9^b to prevent movement of the blade. The plate 9^b is hinged at one end to the plate 8^b and is secured at its other end preferably by a spring latch 38 on the plate 9^b adapted to coöperate with the walls of a notch 39 in a supporting frame 115 40. The latter is rigidly secured to one end of the blade holder so said holder is unsupported between its ends, a portion of the frame 40 lying beneath but in spaced relation to the holder in order that there will 120 be provided a space for the passage of a strop or other sharpener. The frame may have means, preferably in the form of an opening 41 with internally threaded walls, permitting the handle bolt 14 to be secured 125 130

thereto so that the handle may lie perpendicularly to the longitudinal axis of the blade, a sleeve 15, as in Figs. 1 to 4, surrounding the bolt and having a notch 17 at 5 its upper end to receive a projection 16 on the frame 40 and prevent the handle from turning when in shaving position. The frame 40 may also have means which will 10 permit the handle to lie parallel with the longitudinal axis of the blade and to this end a perforation 42 with internally threaded walls is provided. When the bolt 14 is secured in this opening the grip portion can 15 rotate freely so that the device may be manipulated in the same manner as that shown in Figs. 1 to 4.

The guard frame 1^b has a depression between its guard portions 2 to fit beneath the plate 8^b in the manner shown in Figs. 8 20 and 9. In order to support the guard frame in this position, one end of said frame is provided with a projection 43 adapted to enter recess 39 in the frame 40. This projection may be held in recess 39 by a spring 25 latch 44 arranged near the other end of the guard frame and adapted to enter and co-operate with the walls of an inclined recess 45 in the plate 8^b, said latch exerting a pressure in the direction of the length of the 30 guard frame and being removable from the recess either by a pressure downwardly at 46 or a pressure on the spring arm of the latch. A pressure on the latch also permits the latter to enter the recess after the projection 43 has been fitted in recess 39.

In the embodiment shown in Figs. 11 and 12 the blade holder and the frame 40^a are substantially the same as similar parts shown in Figs. 8, 9 and 10. The handle 47 40 is not shiftable on the frame but is secured to an externally threaded hollow boss 49 so as to lie perpendicular to and on one side of the longitudinal axis of the blade.

The guard frame 1^c, instead of being entirely removable, is guided bodily away from the holder. Preferably this is effected by notching one end of the guard frame to provide a guide 50 which co-operates with the guide or support 40^a at the end of the blade 50 holder. The guard frame may also carry a plunger 51 which is movable in the handle, the latter being made hollow for this purpose. To the end that the guard frame may be held in shaving position a nut 52 is journaled in the hollow boss 49 and is adapted to co-operate with a threaded portion 53 on the lower end of the plunger. This arrangement permits the guards to be held at various distances from the blade edges in order that the cutting action of the blade may be varied. Of course the diameter of the threaded portion 53 is greater than the other portion of the plunger 51 so that the latter may pass freely through the nut when dropped to stropping position, as shown in

dotted lines in Fig. 11. During the stropping the handle will lie beneath the strop but the action will be substantially the same as in the other embodiments, that is, when the razor is shifted at each end of the stropping movements the blade edge last engaged will be moved out of engagement with the strop while the opposite edge will engage the strop. 70

From the foregoing it will be seen that I 75 have provided a safety razor in which the blade and the guard may be separated for stropping, the former being rigidly supported without removing it from the holder which supports it during shaving operation. 80 I have also provided a safety razor in which the blade may be moved away from the guard and rigidly supported on the guard frame in stropping relation to the handle as distinguished from supporting the blade 85 directly on the handle. A further result obtained by me is that the handle during stropping lies to one side of the longitudinal axis of the blade so that an edge of the blade co-operates with the strop or other 90 sharpener when the razor is moved in one direction and automatically shifts away from the sharpener when the razor is moved in another direction, this operation having special advantages with a double edged 95 blade as the two edges are alternately sharpened on the movement of the razor. The structure permitting the foregoing also permits the handle to lie substantially perpendicular to the longitudinal axis of the blade 100 for shaving so that a direct pull on the blade may be obtained.

I claim as my invention:

1. A safety razor comprising a guard and a plate to support the blade throughout its 105 length, means connecting said guard and plate so that all portions thereof are movable relatively in parallel lines to provide an opening between them from one end of the blade to the other for the passage of a sharpener transversely of the blade, and means for clamping a blade to said plate, said clamping means being effective as a clamping means when the guard and the plate are separated. 110

2. In a safety razor, a plate for supporting a blade throughout its length, a guard for co-operating with said plate, means connecting the guard and the plate so that they are relatively and bodily movable to provide 115 a space between them from one end of the blade to the other for the passage of a sharpener transversely of the blade, means for clamping a blade to said plate, said means being effective as a clamping means 120 when the guard and the plate are separated, and means for rigidly holding said plate against movement after the separating movement. 125

3. A safety razor comprising a handle, a 130

guard frame rigidly secured to the handle, a blade-supporting plate unsupported between its ends, and supporting connections between the adjacent ends of the guard frame and the plate, said connections having provision permitting the plate to be moved bodily relatively to the guard frame, and means for clamping a blade to the blade-supporting plate, said clamping means 10 being effective as a clamping means when the guard frame and the blade supporting plate are separated.

4. A safety razor comprising a plate having a guard thereon, a blade supporting 15 plate, means connecting said plates so that they are relatively movable to provide a space from one end of the blade to the other for the passage of a sharpener transversely of the blade, means for clamping a blade to 20 the blade-supporting plate, said means being effective as clamping means when the latter and the guard plate are separated, and a handle rigidly secured to one of the first two named elements.

5. A safety razor comprising a guard frame having a guard, a handle rigidly secured thereto, a blade-supporting plate, means for securing said plate against movement out of operative relation with the 30 guard and unsupported between its ends, and means for clamping a blade to the blade-supporting plate, said means being effective as a clamping means when the guard frame and the blade-supporting plate are 35 out of coöperative relation.

6. A safety razor comprising a plate having guards along opposite edges, a handle rigidly secured to said plate, a blade-supporting plate unsupported between its ends, 40 supports rigid with the ends of said plate guided on the guard plate at the ends of the latter to permit a relative movement between the blade-supporting plate and the guard plate, and means for clamping a double-edged blade to said blade-supporting plate, said means being effective as a clamping means when the guard plate and the blade plate are separated.

7. In a safety razor, the combination with 50 a guard frame and a blade holder, one of which is movable relatively to the other to expose the blade for stropping, of a handle, means for holding the blade against movement relatively to the guard frame when spaced for stropping, means permitting the handle to be supported on one of the first two named parts so that said handle lies perpendicular to the longitudinal axis of the blade for shaving, and means permitting 55 said handle to be supported on one of the first two named parts so that the handle and the blade lie parallel for stropping.

8. In a safety razor, the combination with 60 a guard frame, and a blade holder, one of which is movable relatively to the other to

expose the blade for stropping, of means for holding the blade against movement relatively to the guard frame when spaced from the latter for stropping, a handle arranged on the guard frame for shaving so that the 70 handle lies substantially perpendicular to the longitudinal axis of the blade, means permitting one of the two last-mentioned parts to be arranged on the frame in such a position that said parts will lie substantially 75 parallel for stropping.

9. A safety razor comprising a guard frame carrying a guard, a blade holder for holding a blade in coöperative relation with the guard, said blade holder and guard being 80 relatively movable to expose the blade for stropping, means for holding the blade against movement relatively to the guard when spaced from the latter for stropping, a handle, means permitting the handle and the blade holder to be supported on said frame for shaving so that the handle is arranged perpendicular to the longitudinal axis of a blade in the holder, and means permitting said parts to be arranged on said 85 frame so that the handle and the blade holder will lie substantially parallel for stropping.

10. A safety razor comprising a guard frame carrying a guard, a blade holder for 90 holding the blade in coöperative relation with the guard, said blade holder and guard being relatively movable to expose the blade for stropping, means for holding the blade against movement relatively to the guard 95 when spaced from the latter for stropping, a handle having a grip rotatable about an axis longitudinally of the handle, means permitting the handle and the blade to be arranged on the frame so that the handle lies substantially perpendicular to the longitudinal axis of the blade for shaving, means for holding said grip portion against rotation during such arrangement, and means permitting the handle and the blade to be 100 arranged on the frame so that the blade and the handle lie substantially parallel for stropping.

11. A safety razor comprising a guard, a blade, means permitting the blade to be rigidly secured out of coöperative relation with the guard, and a handle arranged parallel with and to one side of the longitudinal axis of the blade when the latter is positioned away from the guard. 120

12. A safety razor comprising a double-edged blade, a blade supporting plate adapted to support the double-edged blade between the two edges thereof, guards coöperating with both edges, means for securing 125 the blade supporting plate out of coöperative relation with the guards to provide a space from one end of the blade to the other for the passage of a sharpener transversely of the blade, and means for clamping the 130

double-edged blade to the supporting plate, said means being effective as a clamping means when the guards and the supporting plate are separated.

- 5 13. A safety razor comprising a blade-supporting plate, a double-edged blade supported between its two edges by said plate, a guard frame having guards coöperating with both edges, and means connecting the
- 10 blade-supporting plate and the guard frame to permit said parts to be moved relatively to provide a space below the blade supporting plate from one end of the blade to the other for the passage of a sharpener trans-
- 15 versely of the blade, and means for clamping the double-edged blade to the supporting plate, said means being effective as a clamping means when the guard frame and the blade-supporting means are separated.
- 20 14. The combination with a guard frame having a guard thereon, of a handle secured to the guard frame, and a blade holder mounted on the guard frame and having rigid supports at each end guided on the
- 25 guard frame to provide a space for the passage of a sharpener and means for holding the blade holder in coöperative relation with the guard on the guard frame.
15. The combination with a guard plate
- having a guard along one edge and slotted 30 near each end, of a handle rigidly secured to the guard plate, a blade supporting plate separate from the guard plate and having rigid supports depending from the ends thereof through the slots of the guard plate 35 to provide a space for the passage of a sharpener and means for holding the blade supporting plate in coöperative relation with the guard on the guard plate.
16. The combination with a guard frame 40 having a central depression and guards on opposite sides of the depression, of a handle secured to the guard frame, a blade holder having means for securing a double-edge blade between the two edges of the latter, 45 lying in and engaging opposite walls of the depression to permit the guards to coöperate with the two edges of a blade in the holder and movable on the frame from the depressions to permit a sharpener to coöperate with the edges of the blade and means for holding the blade holder in coöperative relation 50 with the guards on the guard frame.

HAROLD H. SIMMS.
